LOOM

Carl D. Brown, Hopedale, Mass., assignor to
Draper Corporation, Hopedale, Mass., a corpora-
tion of Maine

Application July 12, 1939, Serial No. 284,028

15 Claims. (Cl. 139—256)

The present invention pertains to automatic looms and more particularly relates to the control and removal of filling ends formed by such looms.

Automatic looms commonly have a reciprocating lay with a shuttle box at the replenishing end thereof, and filling replenishing mechanism for automatically replenishing the filling supply whenever the latter becomes substantially exhausted. Operation of the replenishing mechanism incidentally results in the formation of an incoming filling end which projects from the cloth selvage, and commonly also results in a similarly projecting outgoing filling end. The loom includes parting means such as a temple thread cutter for parting the filling ends adjacent the cloth selvage, and another parting means for parting and clamping the outgoing filling ends adjacent the shuttle box. As constructed commercially, such looms have not commonly included any means whatever for collecting the parted filling ends and removing them from the loom, such ends being left hanging from the magazine of the replenishing mechanism or from the said clamping means.

The filling ends when left hanging as just described are apt to be caught in moving parts of the loom, particularly the lay, shuttle box or picker, and drawn into the cloth, thus forming a defect in the cloth. The problem of collecting and removing the pieces of filling ends to prevent these defects in the cloth has been vexatious and long-standing.

Numerous attempts to solve the aforesaid problem have been made heretofore. For example, it has been proposed to remove the filling ends by a suction pipe located adjacent the shuttle box and connected to a vacuum pump. Other proposals include swinging hooks or arms, operated at the time of filling replenishment, to engage the filling ends and carry them to some point not so close to the lay and shuttle box. However, these prior constructions have been unsatisfactory because they are expensive, complex and unreliable, and they have not been used commercially to any appreciable extent. Thus, in prior looms, the pieces of filling ends are sometimes collected and removed manually, at irregular intervals, but are otherwise left to fall where they may and to be laboriously picked out of the cloth if woven therein.

It is accordingly a principal object of the present invention to provide an automatic loom having a lay, shuttle box, replenishing mechanism, and parting means as aforesaid, and a filling end

remover comprising a conduit leading from a point adjacent the shuttle box to a point remote therefrom, and mechanical means for feeding the filling ends into and through the conduit, whereby such ends shall be automatically prevented from being woven into the cloth. 5

The foregoing and other objects of the invention are accomplished in the construction illustrated on the accompanying drawings, of which:

Fig. 1 is a perspective view of the replenishing 10 side of an automatic loom having the preferred embodiment of my invention applied thereto;

Fig. 2 is a plan view of certain mechanism shown on Fig. 1;

Fig. 3 is a detail view, to a larger scale, showing 15 part of the filling end remover of Figs. 1 and 2; and

Fig. 4 is a view in elevation taken from the left of Fig. 3.

The loom shown on the drawings is but fragmentarily illustrated, the parts and mechanisms not shown being of usual construction which is well known in the art and forms no part of the present invention. In addition, certain of the parts that are shown are old and well known, they 20 being of the present invention only in that they are illustrative of parts that may be used in the combination defined in the appended claims. The old parts include a loom frame, of which part of a right hand loom side 1 and a breast beam 2 30 are shown, and also include a reciprocating lay of which the lay beam 3, reed 4 and shuttle box 5 are shown. The shuttle box 5 is located at the replenishing end of the lay, which in the present instance is at the right hand side of the 35 loom.

A shuttle 6, carrying the filling supply, is picked from side to side of the loom, along the lay beam 3, by suitable means which may include a picker stick 7. As the shuttle is thus picked, it lays 40 filling thread in the shed S which filling thread is beaten into the fell of the cloth C by the reed 4. When the filling supply in the shuttle is substantially exhausted, a fresh supply is provided by suitable automatic replenishing mechanism. 45 The replenishing mechanism may be of any suitable usual construction, such as the bobbin changing mechanism indicated at 8. This mechanism includes a magazine 9 holding reserve bobbins 10 which are transferred to the shuttle as 50 needed. The ends f of the filling on the bobbins 10 are attached to a fixed holder 11 on the magazine.

The transfer of a bobbin 10 to the shuttle 6 and the subsequent picking of the shuttle results 55

in the formation of a length of filling thread which extends from the holder 11 through the shed S. The subsequent beating in of the portion of this thread which is in the shed leaves the end 5 f projecting from the cloth selvage. This filling end is known in the art as the incoming filling end. When the loom is operating with a filling feeler, not shown, the replenishing operation results in formation of another filling end f' projecting from the cloth selvage. This end f' extends 10 from the selvage to the outgoing bobbin in the shuttle and is known as the outgoing filling end. These filling ends are thus formed by operation of the replenishing mechanism but the formation 15 is incidental to the major function, replenishing the filling supply.

The outgoing filling end f' must be parted, at the time of transfer, between the cloth selvage and the shuttle. This parting may be effected 20 by any usual means, that shown including parting and clamping blades 12. These blades are normally closed, to grip a filling end f' as shown, but are moved rearwardly toward the shuttle box and are simultaneously opened, just prior to each 25 replenishing operation. The opening of the blades 12 releases the filling end f' held thereby. Then, as the replenishing operation takes place, the blades are again closed to part and clamp the new outgoing filling end and the blades are again moved forwardly. This parting and clamping 30 mechanism is not of the present invention, it being disclosed and claimed in patent to Stafford, No. 1,552,388, granted Sept. 1, 1925, to which patent reference may be had for a more complete disclosure.

The filling ends f and f' are parted adjacent the cloth selvage by any suitable means, such as the usual temple thread cutter 13. Both such filling ends may be supported between the thread cutter 13 and the thread cutter 12 by a hook 14 which is fixed on the loom frame. This hook is not new, per se, but may be found desirable for reasons that will become apparent. The incoming filling end f may be further supported by a 40 fixed wire 15 which extends over the shuttle box 45 5 adjacent the outer end thereof.

It will be apparent that, even when the hook 14 and support 15 are used, the cutting of the filling ends by cutter 13 leaves the ends substantially 50 free and uncontrolled. The free ends are very apt to float or be blown onto moving parts of the loom, and more particularly onto the lay and shuttle box, from whence they may be carried into the shed S by the shuttle 6, thus causing a 55 defect in the cloth. The defects thus caused, on prior looms, are fairly numerous, and are of serious consequence particularly in the better grades of fabrics including rayon and the like. It is to prevent these defects that I have provided 60 the filling end removing means hereinafter described, for automatically conveying the filling ends away from the moving parts of the loom.

In accordance with the present invention, the said removing means comprises a conduit leading 65 away from the moving parts of the loom, and mechanical means for feeding the filling ends into and along the conduit. The particular conduit 16 shown on the drawings is tubular in form, open at both ends. This conduit 16 is 70 fixed in a bracket 17, which may be supported by the usual bracket 18 for the cutting and clamping mechanism which includes the blades 12. As thus supported, the conduit is located beneath the magazine 9 and directly in front of the shuttle box 5 intermediate the ends of the latter.

The filling ends f and f' withdraw from the shuttle box 5 as the lay moves rearwardly following a replenishing operation. Thereafter, the filling ends project from the cloth selvage longitudinally of the lay, in front of the shuttle box. 5 The rearward end 19 of the conduit 16 is located directly in front of these filling ends, which point is adjacent the shuttle box when the lay is in its forward position. The conduit extends forwardly from its rearward end, to any suitable point that is sufficiently remote from the moving parts of the loom, particularly the lay and shuttle box. The forward end 20 of the particular conduit 16 is located over the top of the usual ejected-bobbin receptacle 21. 10 15

It will be apparent that various suitable mechanical means may be devised for feeding the filling ends into and through a conduit such as the conduit 16. However, the preferred form shown is simple and very effective. This preferred form comprises a member 22 in the form of a plunger. The member 22 has a simple, continuous reciprocating motion which may be imparted by the lay. To this end, the member may be fixed to the lay by being rigidly fixed at its rearward end to a bracket 23 on the front of the shuttle box 5. The member 22 extends forwardly from the bracket 23 into the conduit 16 and is preferably of sufficient length that it is not completely withdrawn from the conduit even when 30 the lay is in its rearward position.

When the member 22 is located as just described, the filling ends f and f' will sag into engagement with the member as soon as they are cut by the temple thread cutter 13. The member 22 has projections 24 which thereupon engage the filling ends and push them forwardly into the rearward end of the conduit 16. The projections 24 extend circumferentially of the member 22 and are radially inclined, each projection having a radial front face and a forwardly inclined rear face as shown more clearly by Fig. 3. When thus formed, the projections are adapted to feed the filling ends in one direction only, i. e., forwardly. 40 45

The total movement of the member 22 is appreciably less than the distance the newly formed filling ends must travel to emerge from the front end of the conduit 16. The member 22 accordingly must reciprocate several times, feeding the filling ends forwardly with an intermittent motion, to feed the ends entirely through the conduit. In other words, the member 22 feeds the ends forwardly a short distance, then moves rearwardly leaving the ends stationary, and then feeds the ends forwardly, etc. The 50 particular construction shown is effective to produce the desired intermittent feeding action, only if the conduit is provided with means for preventing retrograde or rearward movement of the filling ends. Means for this purpose may consist of any suitable material which is of a nature to or has the property of adhering to the filling ends. A suitable material may consist of a pile fabric, or a piece of sheepskin with the wool properly clipped. The material is located adjacent the forward end of the member 22 and preferably, as shown at 25, is fixed within the conduit 16 with the wool or pile 26 on the inside and in engagement with the member 22. 55 60 65

I find that with the construction above described, the outgoing filling end f' is very rapidly fed entirely through the conduit 16 and dropped in the receptacle 21. The incoming filling ends f are likewise fed through the conduit as far as permitted by their connection to the holder 11. 70 75

While a number of incoming filling ends accumulate in the conduit, they may be broken by a single movement of the operator's hand and then will promptly feed through the conduit and fall into the receptacle 21. In the meantime, these ends are effectively held entirely out of any position where they might be caught and carried into the cloth.

Having fully disclosed the preferred embodiment of my invention, I claim:

1. In an automatic filling replenishing loom, the combination of the reciprocating lay, filling replenishing mechanism forming the usual incoming filling ends projecting from the cloth selvage, a conduit extending from a point adjacent the incoming filling ends to a point remote from the moving parts of the loom, means for parting said filling ends adjacent the cloth selvage, and reciprocating means for feeding the parted filling ends into and through said conduit.

2. In an automatic filling replenishing loom, the combination of the reciprocating lay, filling replenishing mechanism forming the usual incoming filling ends projecting from the cloth selvage, a conduit extending from a point adjacent said replenishing mechanism to a point remote therefrom, means for parting said filling ends adjacent the cloth selvage, and reciprocating means engaging the parted filling ends and feeding them into and along said conduit.

3. In an automatic filling replenishing loom, the combination of the reciprocating lay having a shuttle box at the replenishing end thereof, filling replenishing mechanism, said mechanism automatically replenishing the filling supply and incidentally forming incoming filling ends which project from the cloth selvage, a conduit extending from a point adjacent said filling ends in front of said shuttle box to a point remote from said lay, means for parting said filling ends adjacent the cloth selvage, and mechanical means constructed and arranged to engage the parted filling ends intermediate the ends thereof and feed them into and along said conduit.

4. In an automatic filling replenishing loom, the combination of the reciprocating lay, filling replenishing mechanism including a magazine, operation of said mechanism incidentally forming the usual outgoing and incoming filling ends which project from the cloth selvage, a conduit extending from a point beneath said magazine adjacent said filling ends to a point remote from the moving parts of the loom, means for parting said ends adjacent the cloth selvage, and a single mechanical means engaging both said outgoing and incoming filling ends and feeding them into said conduit.

5. In an automatic filling replenishing loom, the combination of the reciprocating lay, filling replenishing mechanism, said mechanism incidentally forming incoming filling ends projecting from the cloth selvage, a conduit extending from a point adjacent said replenishing mechanism to a point remote from the moving parts of the loom, means for parting said filling ends adjacent the cloth selvage, and mechanical means operated by the lay for engaging said filling ends and feeding them into and along said conduit.

6. In an automatic filling replenishing loom, the combination of the reciprocating lay, filling replenishing mechanism, said mechanism incidentally forming incoming filling ends projecting from the cloth selvage, a conduit extending

from a point adjacent said replenishing mechanism in front of the lay to a point remote from the moving parts of the loom, a temple thread cutter for cutting said filling ends adjacent the cloth selvage, and toothed means traversing the interior of said conduit for engaging the cut filling ends and feeding them to and through said conduit.

7. In an automatic filling replenishing loom, the combination of the reciprocating lay having a shuttle box at the replenishing end thereof, replenishing mechanism located adjacent said shuttle box, said mechanism incidentally forming incoming filling ends projecting from the cloth selvage, a fixed conduit extending forwardly from a point adjacent said shuttle box to a point remote therefrom, means for parting said filling ends adjacent the cloth selvage, and a continuously reciprocating member constructed and arranged to engage the parted incoming filling ends and feed them into and forwardly along said conduit.

8. In an automatic filling replenishing loom, the combination of the reciprocating lay having a shuttle box at the replenishing end thereof, replenishing mechanism located adjacent said shuttle box, said mechanism incidentally forming outgoing and incoming filling ends projecting from the cloth selvage, a fixed conduit located adjacent said shuttle box and extending forwardly therefrom, means for parting said filling ends adjacent the cloth selvage, and a member carried by said lay and constructed and arranged to engage the parted outgoing and incoming filling ends and push them into and forwardly through said conduit.

9. In an automatic filling replenishing loom, the combination of the reciprocating lay having a shuttle box at the replenishing end thereof, replenishing mechanism located adjacent said shuttle box, said mechanism incidentally forming outgoing and incoming filling ends extending from the cloth selvage and in front of said shuttle box, a fixed conduit located in front of said shuttle box intermediate the ends thereof, said conduit extending forwardly from a point adjacent said filling ends, means for parting said filling ends adjacent the cloth selvage, and a member supported on the lay and arranged to feed said filling ends into and through said conduit.

10. In a filling end remover for automatic looms, the combination of a conduit leading away from the moving parts of the loom, a continuously reciprocating member constructed and arranged to engage the filling ends and feed them into and along said conduit, and means for reciprocating said member as aforesaid.

11. In a filling end remover for automatic looms, the combination of a fixed conduit leading away from the moving parts of the loom, a reciprocating member constructed and arranged to engage the filling ends and feed them into and along said conduit, and means for reciprocating said member, said member having radially inclined projections for feeding said filling ends in one direction only, and said conduit having means for preventing movement of said filling ends in the opposite direction.

12. An automatic loom having filling replenishing mechanism, a reciprocating lay, and a filling end remover, said end remover comprising a fixed conduit leading away from said lay and a filling end feeding member reciprocating within said conduit, said member having inclined projections for feeding said filling ends intermit-

tently along said conduit, and said conduit having holding means for preventing retrograde movement of said filling ends.

13. An automatic loom having filling replenishing mechanism, a reciprocating lay having a shuttle box at the replenishing end thereof, and a filling end remover, said remover comprising a fixed conduit extending forwardly from a point in front of said shuttle box, and a filling end feeding member fixed to said lay and extending forwardly within said conduit, said member having forwardly inclined projections engaging said filling ends and feeding them forwardly intermittently, and said conduit containing holding means for preventing rearward movement of said filling ends.

14. An automatic loom having filling replenishing mechanism, a reciprocating lay having a shuttle box at the replenishing end thereof, and a filling end remover, said remover comprising a plunger fixed to said lay adjacent said shuttle box and extending forwardly therefrom and a holding material fixed adjacent the forward part of said plunger, said plunger having a multiplic-

ity of forwardly inclined projections engaging said filling ends and feeding them forwardly along said material, and said material being of a nature to adhere to said filling ends sufficiently to prevent rearward movement thereof.

15. An automatic loom having filling replenishing mechanism, a reciprocating lay having a shuttle box at the replenishing end thereof, and a filling end remover, said remover comprising a fixed conduit extending forwardly from a point in front of said shuttle box, and a filling end feeding member fixed to said lay and extending forwardly within said conduit, said member having a multiplicity of longitudinally spaced circumferential ridges, each of said ridges having a radial front face and a forwardly inclined rear face whereby said ridges engage and feed the filling ends forwardly step by step, and said conduit being lined with a material having the property of adhering to said filling ends sufficiently to prevent the ends from moving rearwardly with said plunger.

CARL D. BROWN.
